UNITED STATES PATENT OFFICE.

WILLIAM EVENSEN, OF CHICAGO, ILLINOIS, ASSIGNOR TO GOSS PRINTING PRESS COMPANY, A CORPORATION OF ILLINOIS.

STEREOTYPE-PLATE-CASTING MACHINE.

Application filed February 17, 1921. Serial No. 445,781.

To all whom it may concern:

Be it known that I, WILLIAM EVENSEN, a citizen of the United States, residing at Chicago, in the county of Cook and State 5 of Illinois, have made certain new and useful Improvements in Stereotype-Plate-Casting Machines, of which the following is a specification.

The invention relates to stereotype plate 10 casting machines, and more especially to improvements in the casting mechanism proper, that is, the elements constituting the casting chamber and the parts cooperating therewith.

15 Objects and advantages of the invention will be set forth in part hereinafter and in part will be obvious herefrom, or may be learned by practice with the invention, the same being realized and attained by means 20 of the instrumentalities and combinations pointed out in the appended claims.

The invention consists in the novel parts, constructions, arrangements, combinations and improvements herein shown and described.

25 The accompanying drawings, referred to herein and constituting a part hereof, illustrate one embodiment of the invention, and together with the description, serve to explain the principles of the invention.

Of the drawings:

Fig. 1 is an end elevation, with parts in vertical transverse section, of a casting machine embodying the present invention;

30 Fig. 2 is a fragmentary, enlarged detail, in transverse section, of the casting core, pump nozzle and the drag, which are shown at the upper central part of Fig. 1, but showing them in casting position just after the plate has been cast;

Fig. 3 is an elevation of the casting cylinder or core, looking thereat from the left in Fig. 2 and from the bottom in Fig. 4, the parts at the right of the figure being 40 shown in vertical central section;

Fig. 4 is a detached detail, in top plan, of the casting core, the matrix holding clips

and associated parts, looking at Figs. 2 and 3 from the top;

Fig. 5 is a perspective of the end ring 50 of the casting chamber, showing especially the guide and shoulder for the plate, when it is being rotated from casting to discharge position;

Fig. 6 is a fragmentary detail in front elevation of the pump nozzle;

Fig. 7 is a fragmentary top plan corresponding to Fig. 6; and

Fig. 8 is a transverse section on line 8—8 of Figs. 6 and 7.

In casting hemi-cylindrical stereotype plates for rotary printing presses, it is customary to have the cylinder or core of the casting machine of slightly less diameter than the form or plate cylinder of the printing press, so that the stereotype plate when put on the press will spring over the plate cylinder and hold tightly to the cylinder. Furthermore, in practical work, in making up the forms, composed usually or mostly 65 of linotype slugs, the columns as made up are frequently over-length. By way of example, in a page having columns of twenty inches standard length, the pages as actually made up, and the matrix sheets made 70 therefrom, will have the columns running to twenty and five-eighths inches long; also, the standard twenty-one inches column pages will often run to about twenty-one and three-quarter inches in length, as will 75 also the twenty-two inch column pages.

The foregoing is a practical example of the application of the invention under the present practice of casting plates with the columns extending around the press cylinders. The invention is also applicable to produce extra long plates set in pages without columns. Also, if the columns run along the cylinder, the invention will produce columns of extra width, or an extra column 85 on the plate, as the case may be. The invention provides a novel relation of the plate to the casting mechanism, and the reference in the description and claims to a 90

plate with extra length columns will be understood, as expressing the present most practical application of the invention.

By reason of the over length of the pages, and by reason of the relative smallness of the casting core, and also with the risers at each end of a plate in a machine where the metal is poured at a straight edge of the casting chamber, it is frequently found that the plate will extend about the casting core for an appreciable distance more than a semi-circumference of the core. In such case, the plate is sprung in removing it from the casting core, and consequently will not fit tightly on the press cylinder. Also, the casting machines as ordinarily built are either unable or not well adapted to casting plates of such extra column length.

According to the present invention, the core of the casting machine is composed of two hemi-cylindrical parts, with their axes parallel but slightly separated from one another; the core, however, rotating about an axis in the common plane of, parallel to, and equally distant from, the axes of the two hemi-cylindrical parts of the casting core. The exterior of the core is a continuous surface, so that the core may present a casting surface at the casting chamber and a cast plate at delivery position by a half rotation of the core for each casting operation.

By way of example, with columns of the length already stated as being in common practical use, to provide for the extra length required, the axes of the hemi-cylinders would be about five-eighths of an inch apart. With a casting core so constructed and with the exemplary dimensions given, which as stated are those or some of those frequently found in newspaper press rooms, the stereotype plate will extend very little, probably about only one-half inch over the center of the core, which with the construction described permits the overlength plates to be cast and avoids injurious springing of the plates in removing them perpendicularly away from the core.

Referring now in detail the embodiment of the invention illustrated by way of example in the accompanying drawings, the invention is shown applied to a stereotype plate casting machine having a horizontally disposed, rotatable core, with the concave casting member located beneath the core and reciprocable upwardly to, and downwardly away from, casting position. The core makes a half rotation, to bring a cast plate to its top side preparatory to delivery thereof, and to present the other casting surface at the bottom side of the core, ready for casting, the hot metal being poured at one of the straight edges of the casting chamber. Such a machine may be of the general form shown in applications Ser. No.

407,984 and Ser. No. 407,985 of Joseph J. Walser filed Sept. 3, 1920, and is illustrated in Fig. 1 of the present drawings.

As the present invention relates to the casting mechanism, only an end view of the entire machine is shown (Fig. 1), illustrating the general form and arrangement of a casting mechanism of the kind already described, although it will be understood that in many of its features, the invention is applicable to casting machines of other forms and constructions.

As so embodied, the machine comprises a casting core 1 having a shaft or pintles 2 and 3 projecting from the ends thereof, and journaled, as usual in the machine frame. Cooperating with the core 1 is a concave or drag member 10, these two constituting the main elements of the casting chamber. In the embodied form, the casting core 1 makes a half rotation for each casting operation, the core carrying the plate with it from casting to delivery position, and the concave 10 is located on the under side of the horizontally-disposed casting core and reciprocates vertically up to, and downwardly away from, the casting position.

Suitable matrix-stripping devices are provided for stripping the matrix from the cast plate as the member 10 recedes from the casting position, and these may be automatically spring operated, and may be of the general form shown and described in application Ser. No. 408,203 of Albert A. Henzi, filed Sept. 4, 1920. The matrix clamps are shown in the matrix stripping position in Fig. 1 and are shown in casting position in Fig. 2, and need not be described in detail.

Suitable mechanism is provided for imparting the periodic or successive half rotations to the core 1, and this mechanism may be of the form shown in the Walser application referred to, and certain parts thereof are indicated by reference numeral 11 in Fig. 1 of the present drawing. This mechanism is driven from a general driving and cam shaft 12. The drag or concave 10 may be reciprocated to and from casting position in any suitable manner, and as shown, is provided with guideways 13 and 14, running on guides formed in the machine frame 15. Mounted on the underside of the drag 10, and centrally thereof, are longitudinally spaced-apart cam rollers 16, which cooperate with cams 17. Cams 17 are mounted upon and rotate with the shaft 12 to impart the described movement to the concave casting member 10.

In Fig. 2 of the drawings is shown in detail the present preferred embodiment of the casting core or cylinder. The casting core has two opposed casting faces, each formed about its own axis, the two axes being spaced apart, whereby the core is somewhat longer on the diameter passing through the centers

of the two casting faces than on the diameter which is perpendicular to said first-mentioned diameter. The core presents a continuous external surface, having two comparatively or substantially flat areas, one at each side, between the semi-cylindrical surfaces just described. The core rotates about an axis located between and in the common plane of the respective axes of the two semi-cylindrical casting parts already described.

As embodied, and considering the core in the position shown in Fig. 2, the upper cylindrical portion of the core is cast or machined, or otherwise finished, about an axis 25, the distances 25-26, 25-27 and 25-28 being radii of the hemi-cylinder, the semi-circumference thereof being represented by the line 27-26-28. This represents one of the plate casting surfaces, or rather the greater part thereof, as the straight edges of the plate and the riser or risers may extend somewhat beyond this, to realize the advantages of the machine in taking care of extra-long plates when this is found to be necessary or desirable.

The other hemi-cylindrical part of the core has its axis at 29, the distances 29-30, 29-31 and 29-32 being radii of the hemi-cylinder, the semi-circumference thereof being represented by the line 31-30-32. This represents the other plate casting surface, or rather the greater part thereof, the plate extending past at either of its horizontal sides in the manner already explained in connection with the other casting surface.

The central section of the core may be regarded theoretically as a rectangular solid block interposed between the two equal hemi-cylinders to space them apart along one diameter thereof, while leaving the diameter perpendicular to said first-mentioned diameter unchanged. This construction may be conveniently styled theoretically a cylindroid, although in a practical embodiment it may not be precisely of that form. In Fig. 2 the lines 27-31 and 28-32 may be straight or substantially straight, and the corresponding areas along the cylinder, may be flat or approximately, or substantially flat.

The core rotates about an axis disposed longitudinally thereof at the central point of its long diameter or dimension, represented by the line 26-30 in Fig. 2, which would be an axis 33, parallel to the axes 25 and 29 and lying midway between them, and in their common plane. It will be understood that in actual practice there may not be strict conformity to the geometrical terms and construction, although such a description is deemed best adapted to explain the principle of the invention.

As stated, the cast plate α is carried from the casting position to delivery position by the half rotation of the core 1. Toward the

close of this movement of the core, as shown in Fig. 1, the leading straight edge of the plate α strikes a stop 39, and at the same time a traveling stop or pusher 40, mounted in guideways 41 and reciprocated by means of a pivoted connecting rod 42 through a cam and lever mechanism (not shown) from the shaft 12, enters beneath the rear or following straight edge of the plate α and then lifts the plate upwardly from the cylinder 1 to the position shown in Fig. 1, ready for delivery. Just prior to the half rotation of the casting core 1, the concave 10 begins its downward movement, the matrix γ being stripped from the plate as shown in Fig. 1. The concave 10 then moves back and just after the core 1 has come to rest it is back in casting position. If it is desired to change the matrix sheet γ this can be done when the concave 10 is in receding position.

Suitable end plates, or "end rings" as they are usually called, are provided to form or limit the semi-circular ends of the casting chamber, and at the same time providing for the removal of the cast plate from the casting position with a rotating core of the form described, and providing also for the delivery of the plate by lifting it slightly from the core and then moving it away in a direction longitudinal of the core.

As embodied, at what may be conveniently termed the outside end of the plate (Figs. 3 and 4), an end plate 50 is provided of, or approximately of, semi-circular form, mounted independently of the rotating cylinder, and bearing against the lower half of the flat end of the core 1, the outer periphery 51 of said end plate bearing against the drag or concave 10 and the inner flat face 52 of the end plate bearing against the flat side or end of the core cylinder 1. The ring thus constitutes a closure for this end of the casting chamber and always remains in operative position at the casting chamber, as it does not rotate with the core.

The end plate 50, in addition to closing that end of the casting chamber and holding down the curved end of the matrix sheet γ , is also designed and intended to hold the plate α in position on the core 1 during the rotation of the core, as the plate is thereby carried upwardly to delivery position on the top side or just above the core. Due to the fact that the cast stereotype plate α during the rotation of the core is not moving about its own axis 29, but is moving about the axis of rotation 33 of the core, the central part of the plate follows a path lying outside of the circumference of the plate α when in casting position.

For the purpose indicated, and in view of the described movement of the plate, the end plate 50 (Figs. 3 and 5) is provided with a projection or flange 53, extending from the flat side of the end plate into the

casting chamber just over the end of the matrix y , and formed and proportioned so as to form a shoulder in the curved end of the plate x as shown in Fig. 3. This flange 53 is thickest at the lowermost point of the core, that is, at the central point of the curved or arcuate end of the casting chamber, and decreases in thickness outwardly towards the ends of the ring 50, as shown in Fig. 5. In other words, the outer curved or peripheral face of flange 53 is concentric with the center 29 of the casting surface of the core and of the concave 10, while the inner curved or peripheral face 54 of the ring, along which the corresponding shoulder 55 in the stereotype plate x slides during the rotation of the core, is a semi-circumference, or approximately a semi-circumference concentric with the axis 33 (which it will be recalled is the axis of rotation of the core) thereby providing a continuous, true bearing surface for the central point of the shoulder 55 on the plate x until the plate is about half way through its rotational movement with the core 1.

In the embodied form of mounting, the ring 50 is mounted upon the machine frame and is spring-pressed against the flat end of the core 1. As embodied, it is provided with a plurality of recesses, preferably three in number, into which project pins 60, which support the end plate in its general position, but permit sufficient movement thereof to insure tight closing of the end of the casting chamber. Mounted upon the machine frame 61 is a semi-circular hub or flange 62, fitting closely around and back of the ring 50. The pins 60 have enlarged screw-threaded outer portions which are screwed into threaded sockets 65 in the machine frame 61; the pins 60 projecting therefrom through apertures or recesses in the frame and through corresponding recesses or apertures 64 in the hub or flange 62. Nested within the apertures 64 and coiled about the pins 60 are springs 66, which press against the outer flat side of the ring 50, and press it firmly against the flat end of the core 1.

The cooperating mechanism at the opposite end of the casting chamber, as embodied, comprises an end ring, or preferably two segmental and approximately semi-circular end plates, with their ends somewhat separated, mounted opposite each other upon the same end of the core 1. The two end plates are independently adjustable longitudinally of the core 1, to provide allowance or adjustment for matrix sheets and pages of different width. As embodied, for the lower half of the core as shown in Fig. 3 an end plate or "ring" 70 is mounted upon the cylindrical exterior and at one end of the cylinder or core 1, having a somewhat undercut or bevel annular front wall 71 for giving proper form to the adjacent end of the plate.

The "ring" or end plate 70 is made adjustable longitudinally of the cylinder, and for this purpose it is attached to the cylinder by screw bolts 75, passing through elongated slots or openings 72 in the end plate 70, the heads of the screw bolts being countersunk in the plate 70. The longitudinally-disposed slots 72 permit of adjustment of the end ring 70 longitudinally of the cylinder to accommodate matrix sheets of different widths corresponding to different page widths of the form. The outer cylindrical face or periphery 73 of the ring presses closely against the inner surface of the concave 10 when the latter is at casting position, to close that end of the casting chamber, and the ring is slightly undercut at 74 to clamp and protect the end of the matrix sheet y , in a well known manner. The corresponding end ring or plate 70 upon the other half or casting surface of the core 1 may be similar in form and construction, and need not be described in detail.

It will be noted from the foregoing that at its delivery end, that is the end at which or toward which the plate is delivered longitudinally of the cylinder into the trimming mechanism, the end plate or ring 50 is always at the casting position, and the cylinder or core 1 is free from any projection at that end. Thus but a very slight raising of the stereotype plate x away from the cylinder or core 1 is essential before starting the longitudinal movement of the plate x parallel to the cylinder and toward the trimming mechanism or other place of delivery as the case may be.

The relation of the matrix holding and stripping clamps to the foregoing mechanism is clearly shown in Figs. 2 and 4. The inner jaw 78 is provided with lugs 79, rotatably mounted upon a shaft 80, which is carried upon brackets 81, formed upon the frame of the drag or concave 10. A suitable helical spring 82 is coiled about the shaft 80 and impels the clamps into the matrix stripping position of Fig. 1. The cooperating matrix clamping jaw 83 is slideable on the top of the jaw 78 to grasp and to release the matrix y , and is held in matrix-clamping position by suitable means, such as clamping bolts 84, although in actual practice some more quickly-operating device is usually employed. The faces 85 of the clamp constitute a closure for the straight edges of the casting chamber, and will also fit tightly over the straight ends of the end plates or rings 50 and 70. This action is possible with respect to the plates 70 by reason of the spacing between the ends of the two plates circumferentially about the cylinder.

The embodied form of means for supplying the hot stereotype metal to the casting chamber and devices cooperating therewith,

together with the novel devices for increasing their efficiency, comprise a pump of suitable form and a furnace or other means for maintaining a supply of hot metal. So far

5 as concerns the present invention, the general features thereof may be of any suitable or convenient form. As herein shown they are of the general form illustrated and described in the Walser application Ser. No. 10 407,985, filed September 3, 1920, already referred to. The melting pot or furnace is indicated in the present drawings by 90 and the pump by 91, the pump being automatically operated by means of a pivoted connecting rod 92, a lever 93, a rod 94 and a lever 95, from a cam 96.

15 Referring now in detail to the features of the present embodiment, which relate to this particular mechanism (Figs. 1, 2, 6, 7 and 8), the top matrix clamp 83, on the pump side of the machine, is provided with a narrow, elongated slot 97, through which the hot metal is poured into the casting chamber. About the edge of slot 97 there is 20 provided a beaded edge, or fitted bearing surface 98, which surrounds the slot and is adapted to cooperate with a bead, or fitted bearing surface, on the pump nozzle (Fig. 2), of corresponding shape and size. The 25 details of the pump nozzle are shown in Figs. 6, 7 and 8. The pump nozzle has its orifice or throat 106 of narrow, elongated shape to correspond to the slot 97 in the matrix clamp, the hot metal flowing through 30 from the interior 105 of the nozzle and through the slot 97 into the casting chamber.

35 Formed on the underside of the nozzle 99 is a cooperating bead or fitted bearing surface 100, which is, as stated, of the same or 40 corresponding form and dimensions as the bead 98 on the clamp, so that when the nozzle is at casting position, the beads 98 and 100 are in registry and close contact with each other as shown in Fig. 2. Formed also 45 on the upper face of the clamp 83 is a bead or fitted bearing surface 101, and a bead or fitted bearing surface 102 cooperating therewith is formed on the underside of the pump nozzle 99, these two beads registering and 50 engaging together during the metal pumping action throughout the entire width of the nozzle to steady and hold the pump in position and to keep the matrix clamp in proper alignment.

55 Formed also upon the upper front face of the nozzle is a like bead, or fitted surface, 103, which is shaped to fit closely and truly against the side of the core, as shown in Fig. 2. This bead extends for the whole 60 width of the nozzle orifice or throat and then downwardly along both sides of the orifice, as shown in Fig. 2, making a tight closure around the sides and top of the throat against the surface of the core. 65 The lower lip of the orifice is cut away or

recessed inwardly as shown at 104 to permit the flowing hot metal, which is forced through the interior 105 of the pump nozzle to flow down into the casting chamber.

70 One of the advantages of the casting core of the present invention is that it avoids or remedies the objection or disadvantage of too great an overhang from the ends of the arcuate ribs on the back of the stereotype plate to the adjacent straight edge of the 75 plate. This overhang in the usual form of plate is especially long when the columns are somewhat overlength, as already explained. The long overhang is objectionable and detrimental for the reason that the 80 unsupported area between the ends of the ribs and the straight edge of the plate will spring when mounted on the press and impair the printing by that part of the plate.

85 The length of the ribs is governed by the location of the pump nozzle or mouth upon or against the side of the casting core. The nozzle should be clear of the rib-forming recesses 110 of the top half of the core. The additional space provided in the central part 90 of the surface of the core, when in the casting position permits the rib-forming recesses to be lengthened by a like amount or distance, and thus additional length of the ribs 110 brings their ends within effective supporting distance of the straight edges of the plate α , even when the plate is of sufficient size to accommodate the extra-length columns.

95 In the operation of the machine, when the stereotype plate is lifted vertically from the core at delivery position, as already described and as shown in Fig. 1, with the end rings on the core of the form described and shown, the stereotype plate α will move 100 slightly endwise during the lifting movement so that its edge will come out from under the beveled edge of the end ring or plate 70, the rib-forming recesses 110 in the core having a greater angle than the beveled 105 edge 71 of the end ring 70, thus avoiding any tendency to a locking action during the lifting of the stereotype plate.

110 From all the foregoing it will be understood that a mechanism has been provided which realizes the objects and advantages set forth, together with other objects and advantages. It will also be understood that the invention in its broader aspects is not limited to the specific mechanisms shown and described but departures may be made therefrom within the scope of the accompanying claims without departing from the principles of the invention and without sacrificing its chief advantages.

115 120 What I claim is:

125 1. A stereotype plate casting machine, adapted to produce plates with extra length columns, including in combination a core having a casting surface formed about an 130

- axis, the core extending at the sides past said axis, and a concave member forming therewith a casting chamber extending at the sides past the axis of said casting surface 5 on the core.
2. A stereotype plate casting machine, adapted to produce plates with extra length columns, including in combination a rotatable core having opposed cylindrical casting surfaces, each casting surface being formed about its own axis, the two axes being spaced apart slightly within the core, and a concave member cooperating to form a casting chamber extending symmetrically 10 about the core with respect to and past the axis of the casting surface on the core.
3. A stereotype plate casting machine, adapted to produce plates with extra length columns, including in combination a core 15 having a casting surface formed about an axis, the core extending at the sides past said axis, a concave member forming therewith a casting chamber extending at the sides past the axis of said casting surface on the core, and means for pouring in the hot metal at a straight edge of the casting chamber.
4. A stereotype plate casting machine, adapted to produce plates with extra length columns, including in combination a rotatable core having opposed cylindrical casting surfaces, each casting surface being formed about its own axis, the two axes being spaced apart slightly within the core, a concave member cooperating to form a casting 20 chamber extending symmetrically about the core with respect to and past the axis of the casting surface on the core, and means for pouring in the hot metal at a straight edge of the casting chamber.
5. A stereotype plate casting machine, adapted to produce plates with extra length columns, including in combination a core 25 having a cylindrical casting surface formed about an axis, the casting surface extending backwardly past the axis, a concave member cooperating to form a casting chamber, and means for pouring in the hot metal at a straight edge of the casting chamber and back of said axis.
6. A stereotype plate casting machine, adapted to produce plates with extra length columns, including in combination a core 30 having two cylindrical casting surfaces, each formed about its own axis, these axes being spaced apart, a concave member forming a casting chamber extending back of the axis of the casting surface at casting position, and means for pouring hot metal into the casting chamber back of said axis.
7. A stereotype plate casting machine, adapted to produce plates with extra length columns, including in combination a rotatable core having a cylindrical casting surface 35 formed about an axis, the core rotating about an axis behind said axis of the casting surface, a member having a circular surface engaging with a cast plate, to hold it to the core, said circular plate-engaging surface being concentric with the axis of rotation of the core.
8. A stereotype plate casting machine, adapted to produce plates with extra length columns, including in combination a rotatable core having a cylindrical casting surface 40 formed about an axis, the core rotating about an axis behind said axis of the casting surface, a concave member cooperating to form a casting chamber, and an end plate for the casting chamber, having a circular surface engaging with a cast plate, to hold it to the core, said circular plate-engaging surface being concentric with the axis of rotation of the core.
9. A stereotype plate casting machine, adapted to produce plates with extra length 45 columns, including in combination a rotatable core having two cylindrical casting surfaces, each formed about an axis, the axes being spaced apart, the core rotating about an axis between and in the common plane of the first-mentioned axes, a concave casting member cooperating successively with said casting surfaces of the core, and an end plate for the casting chamber having a circular surface engaging a cast plate to hold it to the core, said circular plate-engaging surface being concentric with the axis of rotation of the core.
10. A stereotype plate casting machine, adapted to produce plates with extra length 50 columns, including in combination a rotatable core having a cylindrical casting surface formed about an axis, the core rotating about an axis behind said axis of the casting surface, a concave member cooperating to form a casting chamber, and an end plate for the casting chamber, having a semi-circular flange projecting into the casting chamber with its convex side concentric with the axis of the casting surface to hold down the matrix, and with its concave side concentric with the axis of rotation of the core, to hold the plate to the core as it is carried to delivery by the rotation of the core.
11. A stereotype plate casting machine including in combination a horizontally disposed core having two cylindrical casting surfaces formed about separate axes, the core having two longitudinally disposed approximately flat surfaces at the junctures of the two cylindrical surfaces, a cooperating concave casting member, and a pump with a nozzle discharging the hot metal at one of said flat surfaces of the core.
12. A stereotype plate casting machine including in combination a horizontally disposed core having two cylindrical casting surfaces formed about separate axes, the

core having two longitudinally disposed approximately flat surfaces at the junctures of the two cylindrical surfaces, a cooperating concave casting member, and a pump with a nozzle pressing against and discharging the hot metal at one of said flat surfaces of the core.

13. In a stereotype plate casting machine, a core in the shape of a cylindroid, and an

end plate having a crescent shaped flange, 10 cooperating therewith.

14. In a stereotype plate casting machine, a core in the shape of a cylindroid, and a spring-pressed end plate having a crescent shaped flange, cooperating therewith. 15

In testimony whereof, I have signed by name to this specification,

WILLIAM EVENSEN.
